UNITED STATES PATENT OFFICE.

JOHN A. RENNIE, OF PHILADELPHIA, PENNSYLVANIA.

DESIGN FOR A MAT.

SPECIFICATION forming part of Design No. 30,710, dated May 9, 1899.

Application filed February 10, 1899. Serial No. 705,207. Term of patent 14 years.

To all whom it may concern:

Be it known that I, JOHN A. RENNIE, a subject of Her Majesty the Queen of Great Britain, residing in Philadelphia, in the county of Philadelphia and State of Pennsylvania, have invented and produced a new and original Design for Mats, of which the following is a specification, reference being had to the accompanying drawings, forming part thereof.

10 My invention relates to a new and original design for mats; and the leading or material feature consists in the mat provided with an initial letter of a color contrasting with the body thereof, and the straight portions of said

15 letter having their opposite edges symmetrically disposed or approximately parallel to each other, while the other portions of the latter are composed of squares arranged in a zigzag line, as hereinafter fully described.

20 In the accompanying drawings, Figure 1 is a plan view of a mat constructed according to my design. Fig. 2 is a longitudinal section taken on the plane $\alpha\alpha$, Fig. 1.

In the said drawings, the reference-letter A designates the mat, the body of which is composed of a number of alternately-disposed squares C and D, arranged so as to break joints. 25

The letter E designates the initial-letter "B," the straight portions of which have their opposite edges parallel to or approximately parallel to each other, while the other portions are composed of squares arranged in a zigzag line. The said letter "B" is of a color contrasting with that of the body of the mat, and the opposite parallel edges are indicated by the reference-letter F. 30

What I claim is—

The design for a mat, substantially as herein shown and described.

JOHN A. RENNIE.
